UNITED STATES PATENT OFFICE.

HERBERT HENRY BERRY, OF LONDON, ENGLAND.

ELECTRIC FIRE AND RADIATOR.

Application filed November 29, 1926, Serial No. 151,545, and in Great Britain January 22, 1926.

This invention relates to electric fires or radiators of the kind in which translucent screens are used to enhance the burning fuel effect.

5 As the result of experiments I have found that the burning fuel or fire effect can be greatly enhanced by placing a sheet of irregularly perforated metal, either or both, behind and in front of the screen of coloured 10 glass or equivalent material particularly if the said metal has bright reflecting surfaces because it then produces what appears to be lumps of black coal or other real fuel and bright burning parts thereon.

15 Other devices to further simulate burning may be employed, such as that which I will call a rising spark device and which is later described. My invention may be described as consisting in using this irregularly perforated sheet metal in conjunction with a screen of coloured translucent material in an electric fire having in it one or more electric lights with or without flicker producing devices and with or without heating elements. I will describe my invention with 20 reference to the accompanying drawings, in which:

Fig. 1 shows a sheet of glass or other translucent material say coloured muranese glass 30 suitable for use in front of an electric fire.

Fig. 2 shows an irregularly perforated metal sheet for use behind the glass panel.

Fig. 3 shows another metal sheet for the rising spark effect above referred to.

35 Fig. 4 is a section, on larger scale, of a sheet of perforated metal such as is seen in Fig. 2.

Fig. 5 shows in outline, partly broken away, an electric fire fitted with panels like 40 those seen in Figs. 1 and 2.

Fig. 6 shows part of an electric fire having sheets as 1, 2 and 7 in it and fitted with a rising spark device.

The sheet of glass 1 is shown fitted into the 45 fire in Fig. 5 and has behind it the perforated sheet of metal 2 in which the perforations or openings 3 are of irregular shapes and have side surfaces 4 at various angles and adapted to reflect light from the lamp 5

50 which is fitted into a flicker device 6 constructed as a fan which may have bright blades to enhance the flicker effect. The front of the fire has a vertical groove at each side to receive the glass 1 and the sheet 2 which may be simply dropped into position.

55 In Fig. 6 the glass panel 1 has a sheet, such

as 2, behind it and behind that is a slotted screen 7 such as seen in Fig. 3, and inside the fire I arrange a lantern 8 pivoted over an electric lamp and adapted to be rotated by heat 60 therefrom. This lantern has irregular slots 9 set in opposite relation to those in the screen 7 and so that as the lantern rotates the light seen from the front of the screen appears to move upwardly and as the slots 65 are narrow the result is the rising spark effect above mentioned.

The sheet of metal 2 is preferably bright say polished aluminium so that the reflecting edges, as 4, are easily produced. The unshaded part of the metal will produce the unburnt or black coal, etc. effect whilst the openings 3 with reflecting edges 4 will produce the burning appearance.

70 The drawings show the invention applied 75 to the front of an electric fire or radiator but it can be applied over the top also and be fitted with any suitable "fire place", such as a basket fire or a fire on the top of which imitation wood logs are used such being well 80 known in various forms in connection with electric radiators. If desired other opaque material may be used instead of metal and the reflecting surfaces at the openings there- 85 in need not be provided.

The drawings do not show a metal or other equivalent frame in front of the coloured screen, but if such is used it may be of any convenient form with irregular openings and which will produce an effect resembling 90 coal or other real fuel.

What I claim is:—

1. An electric radiator comprising a frame work constituting the body of the radiator, an electric lamp mounted in the lower part of the frame work, a flicker-producing device positioned above the lamp and actuated by heat therefrom, a coloured translucent screen in front of the lamp and an opaque screen between the coloured screen and the lamp, said opaque screen having in it a number of irregular openings the edges of which are bright and are adapted to reflect light from the lamp. 95

100 2. An electric radiator comprising a frame work constituting the body of the radiator, an electric lamp mounted in the lower part of the frame work, a flicker-producing device positioned above the lamp and actuated by heat therefrom, a coloured translucent screen in front of the lamp and an opaque screen 105 between the coloured screen and the lamp, 110

said opaque screen having in it a number of irregular openings and another screen between the opaque screen and the lamp, the last mentioned screen having in it slot-like openings set at an angle to the vertical, and a lantern device around the lamp and adapted to rotate with the flicker-producing device, said lantern having in it slot-like openings set at inclinations to the vertical and in opposite relation to the slots in the said screen.

3. A radiator arranged to simulate burning fuel and sparks rising therefrom, including an upright frame, an electric lamp mounted in rear of the frame, an opaque screen mounted in the frame in front of the lamp, said opaque screen being formed with openings to permit the passage of light from the lamp therethrough, the edges of the openings being brightened in part to provide reflecting surfaces, a second screen arranged in rear of the opaque screen and in substantial contact therewith, said second screen being formed with a series of substantially uniform slot-like openings to cause the light rays to be controlled by said openings prior to the passage of such rays through the opaque screen, and means whereby the light rays may be controlled in their passage

through the slots of the second screen to cause said light rays to appear to be moving longitudinally of said slot-like openings.

4. A radiator arranged to simulate burning fuel and sparks rising therefrom, including an upright frame, an electric lamp mounted in rear of the frame, an opaque screen mounted in the frame in front of the lamp, said opaque screen being formed with openings to permit the passage of light from the lamp therethrough, the edges of the openings being brightened in part to provide reflecting surfaces, a second screen arranged in rear of the opaque screen and in substantial contact therewith, said second screen being formed with a series of substantially uniform slot-like openings to cause the light rays to be controlled by said openings prior to the passage of such rays through the opaque screen, means whereby the light rays may be controlled in their passage through the slots of the second screen to cause said light rays to appear to be moving longitudinally of said slot-like openings, and a colored translucent screen arranged beyond the opaque screen relative to the lamp.

In testimony whereof I affix my signature.

HERBERT HENRY BERRY.
